UNITED STATES PATENT OFFICE.

CHARLES W. CRAMER AND HARRY C. HAAK, OF SCRANTON, PENNSYLVANIA.

WASHING-MACHINE.

No. 829,631.

Specification of Letters Patent.

Patented Aug. 28, 1906.

Application filed April 2, 1904. Serial No. 201,380.

To all whom it may concern:

Be it known that we, CHARLES W. CRAMER and HARRY C. HAAK, citizens of the United States, residing at Scranton, in the county of Lackawanna and State of Pennsylvania, have invented certain new and useful Improvements in Washing-Machines; and we do hereby declare the following to be a full, clear, and exact description of the invention, such as will enable others skilled in the art to which it appertains to make and use the same.

This invention relates to improvements in washing-machines, and particularly to an oscillating tub.

The object in view is the provision of means for securing maximum leverage and facilitating actuation of a tub for providing for resiliency of movement of such tub.

With this and further objects in view the invention comprises the combination of a pivotally-mounted tub, a spring engaging the outer surface thereof, a lever engaging said spring and pivoted to the pivot of said tub, and means for facilitating actuation of the lever.

It further comprises certain other novel constructions, combinations, and arrangements of parts, as will be hereinafter fully described and claimed.

In the accompanying drawings, Figure 1 is a plan view of the supporting-legs and motor, certain other parts that lie above them being indicated by dotted lines. Fig. 2 is an inverted plan view of the parts illustrated in dotted lines in Fig. 1. Fig. 3 is a transverse vertical section taken on the plane of line 3 3 of Fig. 1. Fig. 4 is an enlarged detail fragmentary perspective view illustrating the improved bracket and surrounding parts.

Referring to the drawings by numerals, 1 indicates the bottom, and 2 the sides, of a tub, which we have referred to as a "tub" throughout this specification and the appendant claims; but we wish it clearly understood that by the term "tub" we mean any element whose oscillation accomplishes a useful function. A bracket 3 is secured to side 2 and bottom 1 and is formed with a projecting hook 4, designed to be engaged by the eye 5 of a helical spring 6, which spring 6 is provided at its opposite end with an eye 7, engaging an eye 8 of an actuating-lever 9. The lever 9 is formed with a sleeve 10 at its inner

end, loosely surrounding and pivotally engaging a vertical shaft 11, suitably journaled in a bearing 12, fixed to supports 13 13. The shaft 11 extends upwardly through the bottom 1 and may be connected to the same in any desired manner.

Formed integral with or fixed to the sleeve 10 and extending from the same on the opposite side from lever 9 is a segmental rack 14, adapted in operation to mesh with a rack-bar 15, fixed to the outer end of a piston-rod 16, carrying a piston of any ordinary type within a cylinder 18. The outer edge of the rack-bar 15 engages and is guided by a suitable limiting-bracket 19, which extends above the upper surface of said rack-bar and prevents lateral play thereof. The end of the cylinder 18, through which the piston-rod 16 projects, is closed by a casing 20, surrounding said rod, and a lubricant-receptacle 26 is arranged to supply lubricant to the piston-rod 16 and is preferably formed with any suitable cap 27.

A supply-pipe 29 communicates with one end of the cylinder 18 for supplying pressure to one side of the piston therein, and a similar pipe 30 communicates with the opposite end of said cylinder for supplying pressure to the opposite side of said piston, the supply of pressure being controlled by a suitable valve 31 of the three-way type adapted to be oscillated for admitting pressure through one of the pipes 29 or 30, while permitting exhaust through the other of said pipes, rocking or oscillating of the valve 31 serving to alternately admit pressure to the opposite sides of the piston in the cylinder 18 for reciprocating the same, and said oscillation of the valve 31 being accomplished by the engagement of lugs 34 and 35, projecting from the stem of said valve, by suitable tripping-fingers 32 and 33. The fingers 32 and 33 are exact duplicates of each other and are carried by radially-extending arms 36 and 37, fixed to the under surface of the bottom 1, the finger 32 being a greater distance from the axis of movement of said bottom than is the finger 33, whereby in operation the finger 32 is adapted to strike the lug 35 and the finger 33 is adapted to engage the lug 34, the lugs 34 and 35 being in different vertical planes, with the lug 34 nearer the pivot of the bottom 1. Each of the fingers 32 and 33 is pivotally supported and provided with a shoulder at one side of its pivot, each of said fin-

gers being thus free to swing away from the respective lug of valve 31 during its rearward travel, while the shoulder of each of said fingers effectually prevents the respective fingers from passing the corresponding lug of valve 31 in its forward travel without throwing the same.

Plates 45 45 rise from the support 13 in the rear of the bracket 19 and are spaced apart and flared outwardly and are adapted particularly for the reception of a bolt 46, slidably carried by the bottom 1, said bolt being adapted to be passed between the plates 45 for locking the bottom positively against movement.

A lug 47 depends from the arm 37 and extends to a plane below the horizontal plane of the upper edge of one of the plates 45, whereby in operation should the bottom 1 swing too far in one direction the said lug will engage said plate and prevent the bottom from moving to such an extent as to cause the tripping-finger 33 to pass the cylinder 18. If the finger 33 should pass the cylinder 18, it will be readily observed that further movement of the bottom 1 would be rendered impossible, due to the fact that while finger 33 could swing in a direction for permitting the same to pass over the cylinder 18 while the bottom 1 is moved in one direction said fingers cannot swing in the opposite direction and could not permit the return movement of said bottom. Therefore the lug 47 is very essential for preventing possible accident, although it is our intention to prevent the swinging of the bottom 1 to a degree for causing the lug 47 to engage the plate 45.

In operation fluid-pressure is admitted from any suitable source through one of the passages in valve 31 into pipe 29 and thence into the cylinder 18, throwing the piston to the opposite end thereof to that in which the same is located when in the position indicated in Fig. 1. This movement of the piston causes rack 15 in meshing with the teeth of segment 14 to actuate said segment and swing the same upon the shaft 11 as a fulcrum, whereby the lever 9 will be caused to travel through the arc of a circle and movement is imparted from said lever through the spring 6 and bracket 3 to the tub-carrying bracket, the spring 6 serving to take up any sudden jerks and to produce a resilient movement of said tub, cushioning and effecting a recoil of the same at the end of the stroke of the lever 9. When the piston has reached the limit of its movement, the tub actuated thereby will have been given sufficient momentum to partially expand the spring 6, which spring after overcoming such momentum retracts and starts the said frame in its reverse movement. Just before the tub arrives at the extreme of its first movement, assuming the machine to have started

70 with the parts in the position indicated in Fig. 1, the latch 32 will engage lug 35 and throw the valve 31 into a position for opening communication between the pressure-supply and pipe 30, said pipe 30 having previously been in communication with that passage in said valve 31 leading to the exhaust. When the valve 31 has been thrown, as stated, the pipe 29 is caused to register with that passage in the valve 31 now communicating with the exhaust, and the admission of pressure through pipe 30 into cylinder 18 will cause the piston therein to travel back to its former position, which return movement effects actuation of the segment 80 14 through the operation of the rack 15. As the segmental rack swings back to its former position the lever 9 is caused to move back to its original position, and movement is imparted through spring 6 to the tub engaged by the same, which tub during its return movement gains sufficient momentum for partially expanding said spring 6 at the end of said return movement, whereby the tub is given, by the retraction of the 85 spring, a start on its next oscillation. Just before the said tub reaches the limit of its movement the latch 33 engages lug 34 and swings the valve 31 to its original position, opening communication of pressure to pipe 29 and opening the exhaust to pipe 30. The operation may thus be automatically continued as long as desired, the tub being swung back and forth with a cushioning effect at the close of each stroke of the piston. 90 100

It will be observed that the segmental rack 14 constitutes one portion and the arm heretofore described as lever 9 constitutes the other portion of the actuating-lever engaged by the spring 6, the said shaft 11 forming the fulcrum for the lever made up of the two parts mentioned.

Having thus fully described our invention, what we claim as new, and desire to secure by Letters Patent, is—

1. In a device of the class described, the combination with a pivotally-mounted tub, of a lever fulcrumed on the pivot of said tub, means for actuating said lever, and a spring connecting the lever with said tub.

2. In a device of the class described, the combination with a pivotally-mounted tub, of a rack, means carrying the same and pivotally engaging the pivot of the tub, a spring connected to the tub and engaging said rack-carrying means for transmitting movement therefrom to the tub and means for swinging the rack.

3. In a device of the class described, the combination with a shaft and a tub pivotally carried thereby, of a sleeve surrounding said shaft, an arm extending from said sleeve, a spring connected to said arm and to said tub, and means for oscillating said sleeve.

4. In a device of the class described, the

combination with a tub and a shaft pivotally carrying the same, of a sleeve carried by said shaft, a spring engaging the tub, means connecting said spring with said sleeve, and

5 means for oscillating the sleeve.

6. In a device of the class described, the combination with a pivotally-mounted tub, of a lever fulcrumed on the pivot of the tub, and a spring connected with one end of said lever and adapted to transmit movement therefrom to the tub, the opposite end of the lever being adapted to be actuated for operating the tub.

7. In a device of the class described, the combination with a pivotally-mounted tub, of a sleeve carried by the pivot of said tub, a lever member extending in one direction from said sleeve, a second lever member extending in an opposite direction from said

20 sleeve, a spring interposed between the first

lever member and the tub for conveying movement from one to the other, and means for actuating the second-mentioned lever member.

7. In a device of the class described, the combination with a pivotally-mounted tub, of a sleeve carried by the pivot of said tub, a lever member extending in one direction from said sleeve, a segmental rack extending in the opposite direction from said sleeve, a spring connecting said lever member to said tub, and means engaging said segmental rack for actuating the same.

In testimony whereof we hereunto affix our signatures in presence of two witnesses.

CHARLES W. CRAMER.
